UNITED STATES PATENT OFFICE.

ROBERT A. STEWART, OF NEW YORK, N. Y., ASSIGNOR TO THE INDEPENDENT MANUFACTURING COMPANY, OF CHICAGO, ILLINOIS.

DESIGN FOR A RUBBER-SPONGE CUSHION.

SPECIFICATION forming part of Design No. 30,122, dated January 31, 1899.

Application filed December 28, 1898. Serial No. 700,563. Term of patent 7 years.

To all whom it may concern:

Be it known that I, ROBERT A. STEWART, a citizen of the United States, residing in New York city, in the county and State of New York, have invented and produced a new and original Design for Rubber-Sponge Cushions, of which the following is a specification, reference being had to the accompanying drawing.

10 The accompanying drawing shows a perspective view of my cushion.

As shown in the accompanying drawing, the cushion has a body portion A, from which rise side pieces B, which latter form the essential feature of my design.

What I claim as new is—

The design for a rubber-sponge cushion as herein shown and described.

In testimony whereof I affix my signature, in the presence of two witnesses, this 27th day 20 of December, 1898.

ROBERT A. STEWART.
